COMBINED DISPLAY AND MERCHANDISING PACKAGE

Richard M. Watts, Henrico County, Va., assignor to Reynolds Metals Company, Richmond, Va., a corporation of Delaware

Filed Oct. 6, 1965, Ser. No. 87,346

Term of patent 14 years

The dominant features of my design reside in the portions shown in full lines, it being understood that the broken line representation of merchandise has been omitted from FIGS. 1 and 2 for convenience of illustration.

I claim:

The ornamental design for a combined display and merchandising package, as shown and described.
